The ornamental design for a battery connector cover, substantially as shown and described.

DESCRIPTION

FIG. 1 is a perspective view of a battery connector cover in accordance with one embodiment of the present invention; FIG. 2 is a side view thereof; FIG. 3 is a front elevation view thereof; FIG. 4 is a side view thereof; FIG. 5 is a back elevation view thereof; FIG. 6 is a bottom view thereof; and, FIG. 7 is a top view thereof.

The evenly spaced broken lines shown in the drawings are directed to environment, are for informational purposes only, and form no part of the claimed design.

The surface shading lines on the claimed portion are provided only to indicate the character and/or any contour or curvature of the surfaces. They do not indicate color, texture, markings that actually exist thereon, indicia, graphic representations, surface treatment, or any other ornamentation applied to the article.
